COMBINED ATOMIZING AND VAPORIZING BURNER

Georg Wilhelm Loose, Flensburg, Germany

Application September 14, 1949, Serial No. 115,616

1 Claim. (Cl. 299—140)

1

Burners for non-volatile fuels are known which can be put into operation without the use of a special preheating fuel. For this purpose, an atomizing burner and a vaporizing burner are combined into a unit. The atomizing burner is first put into operation and, as a rule, it is maintained in operation as long as necessary to produce a sufficient preheating, or vaporizing, respectively, of the fuel to be burnt in the vaporizing burner.

Upon shutting off of the atomizing burner, the vaporizing burner takes over the preheating or vaporizing, respectively, of the fuel supplied thereto.

Experience has shown that difficulties arise in the operation of such combined atomizing and vaporizing burners, particularly when different fuels having different viscosity have to be employed.

Even if, in many cases, a combustible mixture of fuel and air is formed, said mixture is not wholly dispersed, which is a highly important condition for complete combustion. In unfavorable cases, a prior art atomizing burner may become completely clogged up by residue particles even before a sufficient preheating or vaporizing, in the vaporizing burner has been achieved. Then it is impossible to put the combined atomizing and vaporizing burner into operation without the help of a readily volatile fuel. Even with less residue formation, a considerable reduction of the operational efficiency occurs since the atomizing burner under the circumstances must be cleaned each time, or at least very frequently.

An object of the present invention is to provide a combined atomizing and vaporizing burner having an adjustable mixing chamber for adapting the atomizing part of the combined burner to the different viscosities of the fuels employed. An adjustable mixing chamber is, in this case, a mixing chamber the volume of which may be changed. When fuels of higher viscosity are used, the mixing chamber has to be larger than when fuels of lower viscosity are employed.

When fuels are used which have only little tendency towards residue formation, a combined burner according to the invention is preferably employed which is provided with a common nozzle for the atomizing and the vaporizing parts of the burner. On the other hand, when fuels having a more pronounced tendency towards residue formation are used, a combined burner with separate nozzles for the atomizing and vaporizing parts is preferred.

2

The invention is described below with reference to the accompanying drawing, in which—

Fig. 1 is a cross-sectional side view of a burner according to the present invention, and

Fig. 2 shows a vertical cross section of a burner having separate nozzles for initial combustion and continuous operation combustion.

In Fig. 1 the mixing chamber space 3 is formed between a pipe spigot 4 and a cap nut 1. The volume of the mixing chamber may be varied by means of an interchangeable base plug 2. The base plug has at least two passages, one of which is an air passage 6 and the other a fuel lead 7 formed as a riser. In the form shown in Fig. 1 the base plug is tapered at both ends, as at 50 and 60, respectively in order to ensure a tight seal on the pipe spigot 4 on the one hand, and on the chamber walls 8 on the other hand. The tapers 50 and 60 may be different so that the chamber volume can be altered very simply by merely inverting the base plug and re-attaching the riser.

When air is pumped into a fuel tank (not shown in Fig. 1) pressure is produced which on the one hand drives air through the air passage 6 and on the other hand forces fuel through the fuel lead 7 into the mixing chamber space 3. Here a dispersed mixture of air and fuel is formed which on account of the pressure is discharged through the mixing chamber orifice 5 into the atmosphere.

It is advantageous to provide a flame shield 9 beyond the mixing chamber orifice 5. The object of this shield is on the one hand to confine the cone of flame and on the other hand to aid in the accumulation of heat, particularly at the beginning of atomizing combustion, and later on in the re-ignition of a mixture of vaporized fuel and air.

In the embodiment of Fig. 2 air for the atomizing combustion passes through the air passage 6 and fuel through the fuel lead 7 in the form of a riser into the mixing chamber 3 and thence to the nozzle 15 located within a flame shield 9. In the present case air passage 6 and fuel lead 7 are disposed in a base plug 2. The flame gases or the flame as the case may be take effect on the means which serve for vaporizing combustion. Through the fuel lead 14 fuel is conducted to the pre-heater which is built up of bottom shell 16, top shell 17 and closing cap 18. Sufficient pre-heating takes place in the pre-heater space 28, and then the fuel passes through the further part of the fuel lead 14 past the regulation spindle 21 to the nozzle 30. The burner crown 25 effects an accumulation of heat in the pre-heater proper. After the unscrewing of the closing cap 18, screw-

plug 19 and regulation spindle 21 cleaning by mechanical means can be undertaken.

Under normal climatic conditions the above described atomizing and vaporizing burners work without any trouble. If it is to be used at especially low temperatures then it will be advisable to provide fuel means, for use for atomizing combustion, that will remain volatile under arctic conditions. This may be attained by attaching to the base plug one or more supply leads for volatile fuel. An atomizing and vaporizing burner thus fitted up represents under normal conditions apparatus for the combustion of one fuel only, namely a non-volatile fuel, and under arctic conditions it represents apparatus for the combustion of a volatile fuel for the purpose of bringing about normal conditions, and upon attaining this end apparatus for the combustion of a non-volatile fuel.

Having fully described my invention, I claim:

A combined vaporizing and atomizing burner for non-volatile liquid fuels comprising a nozzle; means forming a variable capacity mixing chamber adjacent said nozzle; said means including a pipe, a cap nut secured to one end of said pipe, said cap nut being provided with an orifice in its end wall, and a plug positioned within said cap nut and secured between said nut and said pipe to define a mixing chamber between the end wall of said nut and said plug, the side walls of said plug at one end having a certain taper engaging the walls of said nut to define a mixing chamber

of a certain size, the side walls of said plug at its other end having a different taper so that said plug may be positioned within said nut in either of two ways to define either of two mixing chambers of different sizes; a source of compressed air in communication with said pipe; a source of non-volatile fuel; conduit means in said plug establishing communication between said pipe and said mixing chamber; and other conduit means in and associated with said plug establishing communication between said source of fuel and said mixing chamber, whereby the fuel is atomized in said mixing chamber and fed to said nozzle.
